WILLIAM GEORGE HARTWIG, OF CHICAGO, ILLINOIS, ASSIGNOR TO ARTHUR FRANTZEN, OF CHICAGO, ILLINOIS.

ELECTRICALLY-CONTROLLED SWITCH MECHANISM.

1,399,116.

Specification of Letters Patent.

Patented Dec. 6, 1921.

Application filed July 9, 1917, Serial No. 179,357. Renewed October 10, 1921. Serial No. 506,917.

To all whom it may concern:

Be it known that I, WILLIAM G. HARTWIG, a citizen of the United States of America, and resident of Chicago, Cook county, Illinois, have invented a certain new and useful Improvement in Electrically-Controlled Switch Mechanism, of which the following is a specification.

My invention relates to electrically-controlled switch mechanism of the kind shown and described in my co-pending application, Serial No. 178,236, filed July 2, 1917, in which I have claimed my invention broadly, and is in the nature of an improvement thereon.

The object of my present invention is to provide an improved and novel construction and arrangement whereby a two-point thermostat, such as an ordinary thermometer-thermostat, may be used in place of the three-point thermostat shown and described in said other application, and whereby two conductors leading to the thermostat will be sufficient.

To these and other useful ends, my invention consists in matters hereinafter set forth and claimed.

In the accompanying drawings:—

The single figure is a diagram illustrating an automatic regulating system provided with an electro-magnetically-operated switch-mechanism which is controlled by a thermometer-thermostat, thereby to control the operation of the electric motor by which a steam-pipe valve, or any other device, is automatically operated under thermostatic control, embodying the principles of my invention.

As thus illustrated, my invention comprises the current-mains 1 and 2 for supplying an alternating current of, for example, 110 volts, and which are connected to a transformer 3 for stepping the current down to 15 volts, or to any other required voltage. One terminal of the secondary of said transformer is connected by a conductor 4 with the upper stationary contact-point 5 of the thermometer-thermostat A, while the other terminal of said secondary is connected by a conductor 6 with one terminal of the middle coil 7 of the switch-mechanism B, which latter is of the general character shown and described in said other application. The current-main 1 is connected by a conductor 8 with one brush of the rotary alternating cur-

rent-motor C, which latter may be of any suitable or desired character. The other current-main 2 is connected by a conductor 9 with the swinging contact 10 of said mechanism. The lower stationary contact-point 11 of the thermometer-thermostat A is connected by a conductor 12 with the lower terminal of the coil 13 of said mechanism. Said motor has the other brush thereof connected by the damper 14 with the two contact-points 15 and 16 of an ordinary rotary snap-switch D, which latter may be of any suitable, known or approved character. This snap-switch is connected or geared to the motor C, so that after a predetermined amount of rotation on the part of the motor said switch will then be operated. The other two contacts 17 and 18 of this snap-switch are connected, respectively, by conductors 19 and 20, with the stationary contacts 21 and 22 of said switch-mechanism.

With the foregoing construction, the operation is as follows: As shown in the drawing, the mercury *a* of the thermostat A has expanded, under the influence of a rising temperature, until it has made contact with the contact-point 5, thus electrically connecting this contact with the contact-point 11 below. Under such conditions, a circuit is formed from the secondary of the transformer over the conductor 4, through the thermostat to the conductor 12, through the coil 13 to the stationary contact 23, then through the middle coil or winding 7 and over the conductor 6 of the other terminal 90 of the secondary of the transformer, whereby an alternating current traverses this circuit. The coil 13 has a core which attracts the armature E, so that the latter is maintained in the position into which it was tilted about its axis *e*, and the coil 13 also attracts the armature F which is mounted on a spring *f*, whereby the contact 24 of this spring is retained out of engagement with the stationary contact 25, which latter is of any suitable character and connected by a conductor 26 with the lower terminal of the coil 27 disposed at the other side of the center coil. In this way, while the mercury is in engagement with the contact-point 5, the circuit through the coil 27 is maintained open between the contacts 24 and 25, and the circuit through the coils 7 and 13 in series is maintained closed. The coil 7 may have a core, and in such case it will be non-induc-

tively wound, so as to produce no magnetism; but, on the other hand, it may be merely a resistance coil, inasmuch as the purpose of this winding is to increase the 5 resistance of the circuit through the thermostat, so that when the latter opens its circuit, in response to a falling temperature, the break or separation between the mercury and the contact 5 will not be accompanied by 10 an undesirable sparking action. It will be observed that after the armatures E and F are attracted, as shown in the drawing, less current is required to maintain them in this condition, and consequently the resistance 15 prevents sparking, as stated, and at the same time does not interfere with the maintaining of the armature F in position to keep the contacts 24 and 25 separated. Previously, upon the initial engagement of the mercury 20 α with the contact 5, the armature E was in its reversely tilted position, so that the contact 28 carried by the armature was in engagement with the stationary contact 23, whereby the initial circuit from the coil 13 25 to the contact 23 was not through the coil 7, but was from this contact to the contact 28 and over the conductor 29 to the conductor 6, thus energizing the coil 13 to the full extent thereof for the operation of the two 30 armatures. Also, with the armature E in its reversely tilted position, the contact 10 carried by said armature was in engagement with the contact 22, and the movable switch-element 30 of the snap-switch D was in engagement 35 with the contacts 16 and 17, whereby the circuit through the motor was opened. Immediately, however, upon the engagement of the contact 10 with the contact 21, a circuit was completed direct from 40 the current-main 1 over the conductor 8 to the lower brush of the motor, through the upper brush and the conductor 14 to the contact 16, through the movable member 30 to the contact 17, over the conductor 19 to 45 the contact 21, through the contact 10 and then over the conductor 9 to the other current-main 2, whereby current of full voltage was supplied to operate the motor. After a predetermined amount of operation thereof, 50 by the alternating current thus supplied thereto, the motor was automatically stopped by the operation of the snap-switch D—that is to say, by the sudden movement of the member 30 into position to connect together 55 the contacts 15 and 18 of said switch, thus opening the circuit of the motor which includes the contact 21, but placing the circuit-arrangement of the motor in condition to supply current again as soon as the armature E is again returned to its reversely 60 tilted position with the contact 10 in engagement with the contact 22, whereby the motor will then be given another predetermined operation. The tilting of the 65 armature E into its reverse position, when

the mercury α of the thermostat contracts under a falling temperature, is brought about by the deenergizing of the coil 13 and the consequent engagement of the contact 24 with the contact 25, which closes the circuit 70 from the secondary of the transformer over the conductor 4, over the conductor 31 to the spring f , through the contacts 24 and 25 and over the conductor 26 to the coil 27, which latter is inductively wound to energize its 75 core, through the contact 32 with which the other terminal of this coil 27 is connected, through the contact 28 which is at this time in engagement with the contact 32, and then over the conductors 29 and 26 over 80 the other terminal of the secondary of said transformer. The energizing of the coil 27 causes it to attract the other end of the tilting armature E, so that the latter is tilted into position to cause the contact 10 to engage the contact 22, thereby closing a circuit from the contact 18 to the contact 15 of the switch D, as previously explained, and starting the motor. This tilting movement of the armature E, of course, causes the contact 28 85 to disengage the contact 32 and to engage the contact 23, thus automatically opening the circuit through the coil 27, and at the same time placing the circuit-arrangement of the coil 13 in such condition that this 90 coil will be energized as soon as the mercury α expands and again engages the contact 5, which will produce the operations and effects previously described.

From the foregoing, it will be seen that 100 when the circuit of coil 13 is closed in the thermostat, the circuit of coil 27 is opened between the contacts 24 and 25, and vice versa when the circuit of coil 13 is opened in the thermostat the circuit of the coil 27 is then 105 closed at the contacts 24 and 25, whereby these coils can then be energized at the same time, but are each responsive to a different operation of the thermostat, the coil 13 always responding to the control of the thermostat under the influence of a rising temperature, and the coil 27 always responding to the control of the thermostat under a falling temperature. The contact 10, of course, 110 is insulated by a block of insulation 33 from the armature E, but the contact 28 is secured directly to the armature E, so that in practice the conductor 29 will lead to the middle bearing or mounting for the axis or pivot e of the armature, thus including the armature in the circuit. Any suitable frame can 115 be employed for the magnet-structure involving the three coils, and any suitable means can be employed for mounting the armature, and for supporting the stationary contacts of the switch-mechanism.

It will be understood, of course, that the armature E is retained in either position by the friction of the contact 28 with the contacts 23 and 32, and also by the friction of 120

130

- the contact 10 with the contacts 21 and 22, the contacts 10 and 28 being of flexible metal and shaped to slide and bear upon the stationary contacts. Thus, when the armature 5 E is tilted into either position, it will retain that position until the thermostat A either opens or closes the circuit controlled thereby. While the energizing of the coil 13 which continues while the armature E is in the position shown in the drawing, will assist in retaining the armature in this position, it will be seen that when the coil 27 is energized the tilting of the armature into its other position immediately opens the circuit 10 through this coil 27, so that the latter does not then serve in any way to retain the armature in the position into which it is tilted by this coil. But the friction of the contacts 15 will hold the armature in this position.
- 20 What I claim as my invention is:—
1. In a system of electric motor control, in combination with the motor, an electro-magnetically operated switch mechanism provided with contacts and connections to control the supply of current to said motor, energizing circuits for controlling the electro-magnetic operation of said mechanism, devices operated by said mechanism to control 25 said circuits, so that operation of said mechanism opens one circuit and closes another, and means for controlling said circuits to cause the operation of said devices and said motor, said means including electrically controlled contacts in one of said circuits, said 30 motor having a switch operated thereby to automatically control the supply of operating current thereto, coöperating with said mechanism and said means to automatically control the starting and stopping of said 35 motor.
  2. In a system of electric motor control, in combination with the motor, an electro-magnetically operated switch mechanism provided with contacts and connections to control the supply of current to said motor, energizing circuits for controlling the electro-magnetic operation of said mechanism, devices operated by said mechanism to control 40 said circuits, so that operation of said mechanism opens one circuit and closes another, and means for controlling said circuits to cause the operation of said devices and said motor, said means including electrically controlled contacts in one of said circuits, comprising a switch to connect said mechanism 45 with said motor, said switch being operated by the motor itself to automatically stop the
  - operation thereof, means to supply current of relatively high voltage through said switch to operate said motor, and means to supply current of relatively low voltage to operate said mechanism.
  3. In a system of electric motor control, in combination with the motor, an electro-magnetically operated switch mechanism provided with contacts and connections to control the supply of current to said motor, energizing circuits for controlling the electro-magnetic operation of said mechanism, devices operated by said mechanism to control 50 said circuits, so that operation of said mechanism opens one circuit and closes another, and means for controlling said circuits to cause the operation of said devices and said motor, said means including electrically-controlled contacts in one of said circuits, said motor having a switch to automatically stop the operation thereof, said switch and said mechanism operating alternately, said switch and said mechanism each having one position to start the motor in response to one operation of said means and another position to start the motor in response to another operation of said means, and said means including 55 a thermostat in the other circuit.
  4. In a system of electrical control, a main switch having a plurality of energizing coils and a movable armature therefor, energizing circuits for said coils, devices operated by said armature to control said circuits, a thermostat to control one circuit, and an auxiliary switch having means free from control by said armature and governed by said thermostat through the medium of one of said coils to control another 60 circuit.
  5. The structure of claim 4, said means comprising an armature and contacts controlled thereby, and a spring to retract said armature and close said contacts when the 65 armature is released by the coil.
  6. The structure of claim 4, comprising a resistance for connection in series with one of said coils in the circuit extending through the thermostat.
  7. The structure of claim 4, said means being open when said thermostat is closed, and said armature having one position when said thermostat is open and another position when said thermostat is closed.
- Signed by me at Chicago, Illinois, this 20th day of June, 1917.

WILLIAM GEORGE HARTWIG.
